UNITED STATES PATENT OFFICE

1,922,380

FORMING MILL

John Lucas, Cleveland, Ohio, assignor to The McKinney Tool & Mfg. Co., Cleveland, Ohio, a Corporation of Ohio

Application November 19, 1931
Serial No. 576,139

8 Claims. (Cl. 153—54)

The present invention relates to rolling mills and more particularly to a mill for cold forming of metallic shapes by the continuous bending of strip stock metal.

5 The rolling mill comprising the present invention is of the type disclosed in a patent to Schraishuhn, No. 1,638,463 patented August 9, 1927 for a rolling mill. This type of machine operates upon the stock progressively by a series 10 of successive passes through which the stock is moved to be continuously formed. The present invention is designed as an improvement over the machine disclosed in this patent.

The principal object of the present invention 15 is to provide a rolling mill having a plurality of pairs of die spindles which are driven from a common driving shaft by means of compact, rugged and durable driving connections, which driving connections are so designed as to permit 20 limited adjustment of the spacing between the spindles of each pair to accommodate different sizes of roller dies.

Yet another object of the invention is to provide driving connections for the roller die elements which are characterized by the simplicity 25 of construction and by the provision of a minimum number of bearings in the housing of the machine for the spindles of the various shafts which carry the driving gears, thereby resulting 30 in a decrease in wear and materially lengthening the useful life of the machine.

A still further object of the invention is to provide driving connections for the various roller die elements in the form of a plurality of gear units 35 which are so constructed and arranged that the stresses existing between the gears of each unit are reduced to a minimum thereby permitting the use of relatively light structural materials in the formation of the gear units.

40 Yet another object of the present invention is to provide a machine of the type disclosed having a plurality of laterally adjustable supporting members for the roller die spindles which supporting members are removable and adjustable laterally of the spindles and which, by their lateral adjustment, will permit installation of an additional set of roller die elements which may be mounted on the die spindles in common with the usual set of roller die elements ordinarily provided by machines of this type. In carrying out this object the interests of economy are furthered in that two sets of roller die elements may be employed, which sets may be put into use simultaneously to form similar or varied metallic shapes.

45 A still further object of the invention is to pro-

vide a rolling machine having a plurality of pairs of forming elements in the form of roller dies, in which the supporting spindles carrying the roller dies may be adjusted to vary the center to center distance between the die elements of each 60 pair, means also being provided for adjusting the inclination of the roller die carrying spindles with respect to each other and for maintaining such adjustment under normal operating conditions regardless of the distance maintained between the 65 spindles of each pair of roller die elements.

Convenience of arrangement of parts, ruggedness of design and comparative inexpensive of manufacture are further desired features that have been borne in mind in the development of production of the invention.

Other objects and advantages of the invention not at this time more particularly enumerated will become more readily apparent as the nature of the invention is better understood, the same consisting in the novel construction, combination and arrangement of parts shown in the accompanying four sheets of drawings in which:—

Fig. 1 is a general perspective view of a machine manufactured in accordance with the principles 80 of the present invention.

Fig. 2 is a perspective view of a driving unit employed in connection with the present invention.

Fig. 3 is a sectional view taken substantially 85 along the line 3—3 of Fig. 5.

Fig. 4 is a perspective view of the gear arrangement forming an essential part of this invention.

Fig. 5 is a side elevational view of a driving unit, 90 parts being broken away in the interest of clarity of the preferred embodiment.

Fig. 6 is a sectional view taken along the line 6—6 of Fig. 5.

Fig. 7 is a side elevational view of a modified 95 form of driving unit, similar to Fig. 5.

Fig. 8 is a sectional view taken along the line 8—8 of Fig. 7.

In all of the above described views like characters of reference are employed to designate like parts throughout.

Referring now to the drawings, the machine involves in its general organization mill units 12, each of the units or stands comprising a rear housing 14 and a front housing 16, which housing is laterally adjustable on the table 10 toward and away from the rear housing 14. In this application eight of the stands 12 and 13 have been shown, but it is to be distinctly understood that a greater or lesser number may be employed if desired. The stands 12 are identical in construction and it is 105 110

thought that a description of one unit will suffice for a description of the others.

To effect lateral adjustment of each front housing 16, a plurality of guide bars 18 are provided on the table 10. These guide bars extend transversely of the table. The front housings 16 are each provided with a groove 19 into which grooves the guide bars 18 extend. Each of the housings 16 is provided with laterally extending flanges 20. On opposite sides of the housings 16 T-shaped grooves 22 are formed in the table 10. These grooves are parallel to the guide bars 18.

A plurality of clamps 24 overlie the flanges 20 of the stand 16 and are secured to the table 10 by means of bolts 26' which extend through these clamps 24 and have their heads disposed within the T-shaped grooves 22. An L-shaped clamp 26 serves to clamp the outer flanges 20 of the end units in position. Thus it will be seen that the stand 16 may readily be clamped by means of these clamps 24 and 26 in any desired adjusted position. The rear housings 14 serve to carry the driving connections for the machine. These housings are removably mounted on the machine and are substantially identical in construction. To this end the table is provided with a wide and comparatively shallow longitudinal groove 11 in which the rear housings 14 are removably disposed. Bolts (not shown) extend through the table and into the housings 14 and serve to retain these housings in position in the groove 11 in a manner to be more fully described hereinafter.

The stand 14 serves to support upper and lower spindles 30 and 32 respectively, which spindles are rotatably carried by the front and rear housings 14 and 16, respectively, of the respective units. To this end the front housing 16 is provided with an open guide portion 34 in which is disposed a bearing block 36.

This bearing block 36 serves to support the outer end of the upper spindle 30. The edges of the bearing block 36 overlap the faces of the stand 16 and is guided thereby in the opening 34. In order to effect vertical adjustment of the bearing block 36 an adjusting bolt 40 extends through the top of the housing 16. This bolt is threaded as at 42 and is provided with a square head 55 to facilitate turning of the same. The lower end of the bolt is rotatably secured in the block 36. Thus it will be seen that rotation of the bolt 40 in one direction or the other will serve to elevate or lower the block 36 by virtue of the threaded connection of the bolt 40 with the top of the housing 16.

The lower portion of the front housing 16 is provided with a bearing 51 for the outer end of the lower spindle 32. This spindle extends through the front housing 16 and, inasmuch as the stand is movable longitudinally of the spindles 30 and 32 these spindles may project completely through the stand 16 as shown in Figures 1 and 2.

The housing 14 of each stand 12 is provided with a compartment 42 in which compartments are contained the bearings for the rear ends of the spindles 30 and 32 and also the immediate driving connections for these spindles. Each housing 14 is provided with a front wall 44 and a rear wall 46, a top wall 48 and a base 50. Secured in the front wall 44 of each housing 14 is a sleeve 52 formed of hardened metal which sleeve provides a bearing race for a plurality of roller bearings 54. The rear end of each spindle 32 is provided with an enlarged portion 56 which is rotatably journalled in the sleeve 52 by means

of the bearings and is held in position by means of thrust washers 58 and 60 and a thrust collar 62 serves to retain the thrust washer 60 in position while an annular face plate 64 fitted around the spindle 32 serves to retain the thrust washer 58 in position. The extreme rear end of the spindle 32 is rotatably journalled in the rear wall 46 of the housing 14 by means of ball bearing units 66 which units are held in position by means of a thrust collar 68 and a washer 70 secured to the end of the spindle 32 by means of a bolt 72. Retaining plates 74 and 76, secured in position by means of cap screws 78 and 80 respectively, further aid in retaining the bearings 66 in position. Thus it will be seen that the rear end of the spindle 32 is rotatably supported by both the front wall 44 and the rear wall 46 of the housing 14.

The rear end of the spindle 30 is rotatably supported in vertically adjustable bearing blocks 80 and 82. The bearing block 80 occupies a position adjacent the rear wall 46 of the housing 14 while the bearing block 82 is disposed within the confines of the front wall 44 of this housing. The bearing blocks 80 and 82 carry bearings 84 and 86 respectively which bearings may be held in position in any suitable manner.

In order to effect simultaneous and uniform adjustment of the bearing blocks 80 and 82, the top wall 48 of the housing 14 is provided with a pair of apertures 88 and 90. A sleeve 92 extends through the aperture 88 and similarly a sleeve 94 extends through the aperture 90. The sleeve 92 is provided with an integrally formed gear 96 at its lower end and the upper end of this sleeve is externally threaded as at 98. The threaded portion of the sleeve 92 receives thereon a pair of lock nuts 100 which lock nuts serve to secure the sleeve 92 in any desired adjusted position. The sleeve 92 is internally threaded as at 102 and threadedly received within this sleeve is an adjusting screw 104 the lower end of which is secured to the bearing block 82. By loosening up on the lock nut 100 the sleeve 92 may be rotated to elevate or lower the adjusting screw and consequently adjust the bearing block 82. The sleeve 94 is substantially identical with the sleeve 92, there being a slight difference however in that the gear 108 which is integrally formed on the lower end of this sleeve, is of less thickness than the gear 96 formed on the sleeve 92. The sleeve 94 is adapted to be locked in position by lock nuts 110 similar to the lock nuts 100. Extending through the top wall 48 of the casing 14 is a plunger 112 having a head 114 formed thereon. Between the head and the top of the wall 48 there is disposed a compression spring 116 normally tending to urge the plunger 112 upwardly. Suitably secured to the lower end of the plunger 112 is a gear 118 having teeth thereon which mesh with the teeth of the gears 108 and 96. It will be seen therefore that when the lock nuts 100 and 110 are loosened and either of the sleeves 92 or 94 rotated to effect vertical adjustment of the bearing blocks 80 or 82, as the case may be, motion will be imparted to the other sleeve through the gear 118 carried by the plunger 112. Inasmuch as the number of teeth provided on the gear 108 corresponds to the number of teeth provided on the gear 96 and inasmuch as the pitch of the internal threads on both sleeves 94 and 92 is the same, simultaneous and even adjustment of the height of the bearing blocks 80 and 82 will be effected.

Should for any reason an adjustment of one

145

of the bearing blocks 80 or 82 be desired independently of the other it is merely necessary to manually depress the plunger 112 until the teeth on the gear 118 will no longer mesh with the 5 teeth on the gear 108. With the plunger in this position either of the sleeves 92 or 94 may be rotated to effect vertical adjustment of the bearing blocks 82 or 80 independently.

All of the spindles of the machine are driven 10 from a line shaft 120 which shaft extends longitudinally through the housings 14 of the units 12.

This shaft 120 is a sectional shaft and each section thereof is contained and rotatably journaled in one of the housings 14 of a respective unit 12. An end 121 of each section of the line shaft 120 projects from the respective housing 14 in which it is journaled and its other end is adapted to mate and be locked to the end 20 of the next adjacent section of the shaft 120 in the next adjacent housing 14. Thus when all of the housings 14 are aligned in the groove 11, which extends longitudinally of the table, these housings may be then bolted by means of the 25 bolts (not shown) to the table so that the sections of the shaft 120 will be locked together. Each section of the shaft 120 is provided with a worm portion 119, which portion meshes with a worm gear 123 carried by each spindle 32. 30 As the line shaft 120 rotates, all of the driven gears 123, together with the spindles 32, on which they are mounted will be rotated.

Carried by each spindle 32 is a gear 59 which gear meshes with a gear 61 mounted on a shaft 35 63 journaled in the housing 14 of the unit 12. One end of a U-shaped bracket 65 is pivotally carried by the shaft 63. Each gear 61 in turn meshes with a gear 67 mounted on a stub shaft 69 journaled in the bracket 65. A gear 71 is 40 carried by the upper spindle 30 and this gear 71 meshes with the gear 67 on the shaft 69. A link 73, one end of which is oscillatably mounted on the bearing block 80 serves to rotatably carry the shaft 69 and thus it will be seen that an 45 idler mounting arrangement has been provided which permits adjustment of the upper spindle 30 without affecting the relative centers of its driving gears. With the above described arrangement of gears, the link 73 serves to maintain the 50 gears 67 and 71 in constant mesh against outward thrust while the U-shaped bracket 65 serves to maintain the gears 61 and 67 in constant mesh against outward thrust relative to each other. Upward movement of the bearing blocks 80 and 55 82 which support the spindle 30 of any one unit will cause inward movement of the upper end of the bracket 65 so that the relative centers between the gears 71 and 67 and between the gears 67 and 61 will remain the same distance apart. 60 The driving connection, as far as the meshing of the gears is concerned is in no way disturbed.

In preparing the machine for the particular work that is to be done, the required number of units 12 are assembled on the longitudinal groove 65 11 end to end with the projecting portion 121 of each section of the line shaft 120 engaging an end of the next adjacent section of the line shaft. The bolts (not shown) are then inserted through the underneath side of the top of the table 10 and are secured to the respective housings 14. The inner roller dies, which are designated at 95 95 are then slid onto the spindles 30 and 32 and the front housings 16 are assembled on the table and positioned over each guide bar 18, the grooves 19 registering therewith, and the clamps 24 and

26 are so positioned on the table that they overlie the flanges 20 of the housings 16. The horizontal flanges of the end clamp 26 overlie the flanges of the end housings. The bolts with their heads (not shown) disposed within the 80 T-shaped grooves 22 are then inserted into the horizontal flanges of the clamps and the securing nuts 26' are tightened so that the front stands 16 are securely held in position. The stands 16 are preferably positioned inwardly, as far as the width of the roller dies 95 will permit to prevent thrust on the spindles 30 and 32. The elevation of the upper spindles 30 may then be adjusted by means of the adjusting mechanism on the front and rear housings of each unit in 85 the manner previously described. 90

Under certain conditions of operation an additional set of roller die elements designated at 95 97 may be mounted on the spindles 30 and 32 on the outer side of the housings 16. If these outer roller die elements are to be employed, they are inserted on the spindles after the inner die elements 95 have been assembled and the housings 16 secured in position. Any suitable retaining means may be secured to the outer end 100 of the spindles 30 and 32 for holding these last mentioned die elements in position. Thus in the operation of the machine two structural shapes may be formed simultaneously from the strip stock or if desired a single structural shape 105 may be formed by a preliminary shaping process in the other set of roller die elements.

In the form of the invention shown in Figures 7 and 8, a driving unit is disclosed, by means of which driving unit the inclination of the upper 110 spindles 30' may be adjusted. The front housing 16 is substantially the same as the other housing shown in the other form of the invention. In this form of the invention the sectional line shaft 120' remains the same, as does the lower 115 spindle 32', its bearing and its driving gear 57'. Carried by the spindle 32' is a sprocket 59' which corresponds to the gear 59 on the spindle 56.

Rotatably mounted on a shaft 69' anchored to the side of the housing 14' is a sprocket 67' 120 and disposed about this sprocket 67' and the sprocket 59' is a sprocket chain 68'. The length of this sprocket chain 68' is such that it will more than accommodate the center to center distance between the sprocket 67' and the sprocket 59'. 125 Consequently there exists a slack in the chain between the two sprockets. A sprocket gear 71' carried on the spindle 30', to which it is keyed, is provided with teeth thereon which engage the chain 68'. The spindle 30' is rotatably carried 130 in a bearing block 82'. This sprocket serves to take up a portion of the slack in the chain 68'.

The bearing block 82' is substantially identical to the bearing block 82 shown in Figure 6. An 135 adjusting mechanism is provided for the bearing block 82' which adjusting mechanism consists in the sleeve 92' lock nuts 100' and adjusting screw 104' all of which parts are similar in every respect to the parts 92, 100 and 104 shown in Figure 6. The inner end of the spindle 30' passes through a set of roller bearings 103' carried by the bearing block 82'. The spindle 30' terminates inwardly of the bearing block 82' and has keyed thereto the sprocket 71' which meshes with the chain 68'. An idler sprocket 79' is rotatably carried by the outer end of a link 73' the other end of which link is pivoted on the lower spindle 32'. A second link 75' has its lower end pivoted as at 77' to a point intermediate the ends 145 of the link 73'. The idler sprocket 79' meshes 150

with the chain 68' at all times and it will be seen that upward movement of the bearing block 82' by means of the adjusting mechanism just described will release some of the slack in one side 5 of the chain 68' while at the same time the idler sprocket 79' will take up this slack in the other side of the chain 68'. In this form of the invention the driving connections are at all times in constant and full mesh although the relative centers between the various sprockets may 10 vary.

The invention is not to be limited to the exact arrangement of parts shown in the accompanying drawings or described in this specification 15 as various changes in the details of construction may be resorted to without departing from the spirit of the invention. Only in so far as the invention has been particularly pointed out in the accompanying claims is the same to be 20 limited.

What I claim is:

1. In a forming mill, a base, a plurality of spindle stands providing front and rear spindle 25 housings, spindle driving means associated with said rear spindle housings, said front spindle housings being adjustably mounted on said base for movement laterally thereof, a plurality of spindles carried by said housings and extending 30 forwardly of said front spindle housing and a pair of forming rolls on each spindle beyond the front spindle housing in a direction away from the rear spindle housing.

2. In a forming mill, the combination with a base having a plurality of transverse guides 35 formed thereon, of a plurality of aligned front spindle housings, said spindle housings having oppositely extending lateral flanges formed adjacent their lower ends, a plate bridging adjacent flanges of each housing, there being a plurality of laterally extending grooves formed in 40 said base between said housings, and a bolt extending through each plate and having an end thereof secured in one of said grooves.

3. In a forming mill, the combination of a base, a pair of housings on said base, one of said 45 housings being slidably mounted for movement transversely of the base, a pair of spindles in said housings, a worm shaft, one of said spindles being rotatably journaled in said housings, a driving gear on said last mentioned spindle meshing 50 with said worm shaft, a second gear on said last mentioned spindle, a bracket having one end pivotally mounted in said housing, a third gear journaled in the outer end of said bracket and meshing with said second gear, a fourth gear journaled in the other end of said bracket and movable therewith, and a fifth gear mounted on said 55 other spindle and meshing with said fourth gear, a link connecting said last mentioned spindle with the free end of said bracket to maintain 60 said fourth and fifth gears in constant mesh, and means for raising and lowering said last mentioned spindle.

4. A device for adjusting the axial inclination 65 of a rotatable shaft comprising a support, a pair of independently movable bearing blocks for rotatably supporting said shaft, a connecting rod connecting each bearing block with said support, a rotatable sleeve 70 threadedly received on each

connecting rod and supported by said support whereby rotation of either sleeve will cause longitudinal movement of its respective connecting rod to adjust the position of said shaft, a gear on each sleeve and a gear pivoted on said support and meshing with said other gears.

5. A device for adjusting the axial inclination of a rotatable shaft comprising a support, a pair of bearing blocks for rotatably supporting said shaft, a connecting rod connecting each bearing block with said support, a rotatable sleeve threadedly received on each connecting rod and supported by said support whereby rotation of either sleeve will cause longitudinal movement of its respective connecting rod to adjust the position of said shaft, a gear on each sleeve and a gear pivoted on said support and meshing with said other gear and means for moving said gear on said support out of engagement with one of said other gears.

6. A device for adjusting the axial inclination of a rotatable shaft comprising a support, a pair of bearing blocks for rotatably supporting said shaft, a connecting rod connected to each bearing block, a sleeve threadedly received on each connecting rod and rotatably mounted in the support, a gear formed on each sleeve, an idler gear normally meshing with each of said gears, a shaft for said idler gear extending through said support, and means for axially moving said last mentioned shaft to disengage said idler gear from one of said other gears.

7. In a forming mill, a base, a plurality of spindle stands providing front and rear spindle 110 housings, said front spindle housings being adjustably mounted on said base for movement laterally thereof, a spindle having a sprocket thereon journaled in said rear housing, a shaft having a sprocket thereon journaled in said rear housing, an endless chain extending over 115 said sprockets, a vertically adjustable bearing block in said rear housing, a second spindle having an end thereof journaled in said bearing block, a sprocket on said spindle engaging said chain and meshing therewith externally of the chain between said first mentioned sprockets, a link pivoted for swinging movement about the axis of said first mentioned spindle, a sprocket pivotally mounted on the free end of the link and adapted to engage said chain intermediate said first mentioned sprockets, and a second link having one end thereof pivoted to said first link intermediate its ends and having its other end pivoted on said second spindle.

8. In a forming mill, a base, a plurality of front spindle stands adjustably mounted on said base for independent movement laterally thereof, a plurality of rear spindle housings having spindle driving means associated therewith and mounted in fixed position on said base, a common drive shaft extending longitudinally of said base and adapted to drive said spindles through the driving means associated with said rear spindle housings, forming rolls mounted on said spindles between said front and rear housings and forming rolls mounted on said spindles in front of said front spindle housings.

JOHN LUCAS.

145
